(57) **CLAIM**

The ornamental design for a motorcycle coil cover, as shown and described.

DESCRIPTION

FIG. 1 is a front perspective view of the motorcycle coil cover of the present invention.

FIG. 2 is a front elevation view thereof.

FIG. 3 is a rear elevation view thereof.

FIG. 4 is a top view thereof.

FIG. 5 is a bottom view thereof.

FIG. 6 is a right side view thereof; and,

FIG. 7 is a left side view thereof.

The rear surface, outer surface portions, lower edge portions and connectors of the motorcycle coil cover shown in broken lines form no part of the claimed design.
